OF CONNECTICUT.

ELEVATING TRANSFER-TRUCK.

1,136,906.

Specification of Letters Patent.

Patented Apr. 20, 1915.

Application filed October 13, 1913. Serial No. 794,873.

To all whom it may concern:

Be it known that we, EDWIN S. TODD and BOUGHTON T. NOBLE, citizens of the United States, residing in Milldale, in the county of 5 Hartford, in the State of Connecticut, have invented certain new and useful Improvements in Elevating Transfer-Trucks, of which the following is a specification.

This invention relates to an elevating 10 truck and more particularly to a two-wheeled elevating truck.

One object of the invention is to provide 15 an apparatus which will be capable of prying the load to be transported off of the floor and holding it in elevated position on the truck during its transportation.

Other objects will appear in the detailed 20 description and annexed claims.

The invention will be described in one 25 embodiment thereof for the purposes of illustrating its preferred form.

In the accompanying drawings: Figure 1 30 is a side view of the elevating truck in one of its elevating positions, showing the platform which is designed to carry the load, partially elevated. Fig. 2 is a side view of the truck prior to the first elevating operation. Fig. 3 is a plan view of the assembled truck. Fig. 4 is a partial sectional view 35 showing the details of the elevating mechanism in one position. Fig. 5 is a similar view showing the parts in another position. Fig. 6 is a plan view showing the method of locking the elevating means.

The truck comprises a rectangular body 40 portion or frame *b* having attached thereto the handles *a*, all mounted on and carried by the wheels on axle *c*. In the forward cross member of the frame, elevating mechanism such as shown in Figs. 4, 5 and 6 is mounted. This mechanism comprises two elevating rods *e* which pass through suitable openings in the cross bar *f* of the frame, and slide freely therein. The upper ends 45 of these rods have attached thereto a transverse supporting angle plate *d*, as shown clearly in Figs. 1, 2, 4, and 5. The lower ends of these elevating rods *e* are designed to engage the floor in the manner shown in Figs. 1 and 2. In each rod there is provided at a given distance below the angle plate an annular slot or a cut in shoulder *m*. At each side of the frame, a plate *g* is mounted on the cross piece *f* to slide thereon, as indicated in Fig. 6, and the horizontal move-

ment of each of these plates is limited by a pin and slot construction as shown. In each plate there is provided a slot *n* which, when in one position permits the rod *e* associated with that plate to pass therethrough.

Referring to Fig. 6: If the plate *g* is moved to the left the rod *e* may pass freely through the slot *n*. If the rods *e* are moved upwardly so that the slots *m* therein are in line with the plates *g* these plates *g* can then be moved to engage the slots *m*. The rounded edge of the slot *n* will enter under the upper shoulder of the slot *m* to latch the rods *e* in an elevated position if the plates *g* are moved to the right (see Fig. 6). In order to move the plates *g* as desired, they are connected by a cross piece *q* (see Fig. 3). Mounted on the cross bar *l*, connected to the two sides or handles *a*, there is a loose sleeve *i* having fastened thereto a handle arm *k* extending to a point just above the cross rod *m'* of the handles *a*. This sleeve *i* has fastened thereto a downwardly extending arm, shown dotted in Fig. 2, to the lower end of which are attached links *h* which extend one to one end and one to the other end of the connecting rod *q*. By this construction it will be seen that if the handle arm *k* is moved upwardly, referring to Fig. 3, the plates *g* will be moved to the left to allow the free movement of rods *e* while if the handle arm *k* is moved downwardly the plates *g* will be moved to the right if slots *m* of rods *e* are in line with plates *g* for the latching operation.

The operation of the truck just described in detail is as follows: Referring to Fig. 2, A platform, shown dotted, is designed to support and constitute a part of the load which is to be moved by the truck. The operator having hold of the handles *a*, swings the truck frame under the platform to the position indicated in Fig. 2, with the elevating rods *e* lowered, as shown in this figure. From this position, the operator lowers the handles *a* to the line indicated by A—A. The truck is then swung to the position shown in Fig. 1 by lowering the handles to the position indicated by line A—A in Fig. 2, and the rear end of the truck frame will pry the platform off the floor during this swinging movement. This prying action is due to the fact that the truck frame is pivoted on the axle *c*. Thus the truck acts as a simple lever in applying

lifting force to the rear end of the platform. The front end of the platform pivots on the floor so that the actual lifting leverage applied to the load is a compound leverage. 5 During this downward movement of the handles it will be seen that the elevating rods *e*, the lower ends of which engage the floor, swing slightly to the left (as viewed in Figs. 1 and 2) but the angle plate *d*, which is under the front end of the platform, does not materially change in elevation 10 from the floor. With the truck in the position shown in Fig. 1, the slots *m* of the elevating rods *e* are in line with the plates *g* so that if the handle member *k* is pushed 15 downwardly the plate *g* will move to the right to latch the elevating rods *e* in the position shown in Figs. 1 and 5. If desired a spring may be provided to turn the sleeve *i* to throw the plates *g* in latching position 20 automatically. If the truck handles are then elevated to a line indicated by B—B, Fig. 2, or any position intermediate line A—A and C—C both ends of the platform 25 carrying the load, will be raised from the floor. The lifting of the handles to the last mentioned position will raise the front end of the platform because it is supported by the angle plate *d*. The rear end of the platform which was raised in the first lowering 30 of the handles is not returned to its lowermost position when the handles are kept on the line B—B, or the intermediate position mentioned during the transfer of the platform. When the platform has been moved 35 to a desired point, the handles *a* may be raised to the position shown in Fig. 2 and the handle arm *k* pulled upwardly to move the plates *g* to the left. This action allows 40 the load on the platform to push the rods *e* and the rear end of the frame *b* downwardly, thereby raising the handles *a* to the position C—C shown in Fig. 2. The parts then occupy the relative positions 45 shown in Figs. 2 and 4. When the platform is thus lowered to the floor, the truck may be removed and used again as desired. Instead of providing slot *m* in rod *e*, the lower end of each rod may be turned down in 50 which case a shoulder will be provided to rest on plate *g* in the elevated and latched position of the rods *e*. Less accurate fitting of the parts will then be necessary than is the case when slot *m* is formed as shown 55 in the drawings.

While we have described one preferred form of our invention, we wish it to be understood that the invention may be carried out in many other convenient forms and the protection asked is, therefore, more particularly pointed out in the accompanying claims.

What we claim is:

1. A transfer truck, comprising a frame 65 provided with a handle, means for pivoting

the frame intermediate its ends, a load supporting mechanism vertically slidable relatively to the frame located between the pivoting means and the handle.

2. A transfer truck comprising a frame 70 provided with a handle, means for pivoting the frame intermediate its ends, a load supporting mechanism vertically slidable relatively to the frame located near one end thereof, together with locking means for 75 said mechanism.

3. A transfer truck, comprising a frame provided with a handle, means for pivoting the frame intermediate its ends, a supporting mechanism movable relatively to 80 the frame, a part of said mechanism being arranged to engage the floor as the handle of the frame is lowered, means to lock the frame and mechanism in the relative position taken when the handle is lowered, all 85 constructed and arranged so that the load is supported at one end by said frame and at the other end by said supporting mechanism.

4. A transfer truck comprising a frame 90 provided with a handle, wheels for supporting the frame, an axle for the wheels, pivotally connected with the frame, an elevating and load-supporting device mounted for relative movement with the frame between 95 the axle and the handle, having a part to engage the floor when the handle is lowered and means to hold the parts in the relative position taken when the handle is lowered.

5. A truck arranged to lift and transfer 100 a load supporting platform, comprising a truck frame pivoted intermediate its ends, supported on wheels and adapted to be inserted adjacent the under side of the platform, a vertically movable supporting means 105 in the frame near the handle end thereof, the upper end of which is designed to engage the under side of the platform, the lower end of which is designed to engage the floor, together with a device to lock said means in elevated position, all constructed and arranged so that when the handle is lowered one end of the truck frame raises one end of the platform which pivots on its other end and said supporting means bears 115 on the under side of the platform so that when the supporting means is locked and the handle raised, the platform will be supported and lifted from the floor.

6. The combination of a truck frame, having a handle and provided with two wheels intermediate its ends, the frame being mounted to rock fore and aft, an elevating mechanism mounted at one end of the frame, together with a platform mounted on vertical standards, all constructed and arranged so that the truck frame may be placed adjacent the under side of the platform and the latter raised by a fore and aft rocking movement of the frame.

7. A transfer truck, comprising a frame provided with a handle and wheels, said frame pivoted intermediate its ends, a movable elevating device mounted near the handle end of the frame having a member to engage the floor when the handle is lowered and cause relative movement between said device and said frame, together with a latch to engage the elevating device and raise it

10 with the frame when the handle is raised.

8. A transfer truck, comprising a frame pivoted intermediate its ends and provided with a handle to rock the frame and wheels, a vertically movable elevating device mount-

ed in the frame, a part of which is adapted 15 to engage the floor and cause relative movement between said device and said frame when the handle is moved in one direction, to rock the frame and a latch to engage said device when the frame is rocked in the other 20 direction, whereby the elevating device and frame move together.
